(57) **CLAIM**

We claim the ornamental design for a cat litter box system system, as shown and described.

DESCRIPTION

FIG. 1 is a perspective view of a cat litter box, which is the smaller of a two-piece cat litter box system, showing the new design, as viewed from the front, right, and top.

FIG. 2 is a perspective view thereof, as viewed from the front, left, and bottom.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a perspective view of a cat litter box system showing the new design, in a separated arrangement, as viewed from the front, right, and top.

FIG. 10 is a front view thereof.

FIG. 11 is a rear view thereof.

FIG. 12 is a right side view thereof.

FIG. 13 is a left side view thereof.

FIG. 14 is a top view thereof.

FIG. 15 is a bottom view thereof.

FIG. 16 is a perspective view of the cat litter box system, in a nested closed arrangement, as viewed from the front, right, and top.

FIG. 17 is a front view thereof.

FIG. 18 is a rear view thereof.

FIG. 19 is a right side view thereof.

FIG. 20 is a left side view thereof.

FIG. 21 is a top view thereof.

(Continued)

FIG. 22 is a bottom view thereof.

FIG. 23 is a perspective view of the cat litter box system, in a ninety degree nested arrangement, as viewed from the front, right, and top.

FIG. 24 is a front view thereof.

FIG. 25 is a rear view thereof.

FIG. 26 is a right side view thereof.

FIG. 27 is a left side view thereof.

FIG. 28 is a top view thereof; and,

FIG. 29 is a bottom view thereof.

The evenly spaced broken lines in the figures illustrate portions of the cat litter box system that form no part of the claimed design. The dot-dash lines shown in the figures represent a boundary of the claimed design and form no part thereof.
